EMMETT M. REEDY, OF DECATUR, ILLINOIS, ASSIGNOR TO MUELLER CO., OF DECATUR, ILLINOIS, A CORPORATION OF ILLINOIS

BUILT-IN VALVE

Application filed March 1, 1928. Serial No. 258,306.

The present invention relates to valves, and more especially to improvements in the construction and operation of built-in valves used with bath tubs, shower baths, lavatory fixtures and the like.

One of the essential features of the invention is to provide a built-in valve casing with a main valve and a stop valve, which valves are so associated that upon the removal of the main valve the stop valve will automatically cut off the supply through the casing.

A further object consists in providing a built-in valve casing with a lateral extension, arranged to project through a wall opening: removably mounting a main valve and a coaxial extending stop valve within the casing, and connecting an escutcheon to the main valve stem for concealing the wall opening and the valve casing.

Other objects and advantages of the invention will become apparent from the following description when taken in conjunction with the accompanying claims.

25 In the drawing;

The figure is a vertical sectional view with built-in valve and its associated parts.

Referring to the drawing, 10 denotes a built-in valve casing provided with the inlet port 11 and the outlet port 12, which ports are shown in parallel relation but which obviously could be angularly positioned with respect to each other. A lateral tubular extension 13 extends outwardly from the casing 10 through a wall or body opening 14 and is interiorly threaded as at 15. The casing 10 is also provided with an annular threaded portion 16 between the inlet and outlet ports. A sleeve 17 extends axially within the extension 13 and is provided at its lower extremity with an exteriorly threaded section or partition 18 which engages the portion 16 of the casing, and is formed with a recess chamber 19 in the under side thereof, which communicates

through a central opening 20 with a chamber 21 that communicates through the openings 22 with an annular compartment 23 of the casing 10, which compartment in turn connects with the outlet 12 through a passage 24.

The outer end of the sleeve 17 is arranged to extend an appreciable distance beyond the wall opening 14 and is provided with a polygonal head or collar 25 for receiving any suitable tool, so as to insert or remove the sleeve from the casing. Preferably positioned between the sleeve 17 and the adjacent wall of the extension 13 is a packing 26 that is held in position by an exteriorly threaded gland nut 27, in engagement with the threaded portion 15 of the casing.

The sleeve 17 immediately above the chamber 21 is internally threaded as at 28 so as to receive a correspondingly threaded portion of the main valve 29, which valve is arranged to be moved into and out of engagement with a valve seat 30 on the upper surface of the section 18 so as to control the supply of fluid through the casing.

An externally threaded removable plug 31 engages the section 16 of the casing and is formed with a central opening 32 which terminates at its lower end in a tapered valve seat 33 and communicates at its upper end with a chamber or recess 34 preferably of polygonal shape for the reception of a suitable tool for inserting and removing the plug from the casing.

A depending stop valve casing 35 is preferably threadedly connected as at 36 to the plug 31, and is provided with a lateral opening 37 which communicates with the inlet port 11 for conducting the supply to the casing. A stop or supplemental valve 38 is mounted in the casing 35 and has a tail piece 39 which is slidably mounted in a hollow annular boss 40 that projects from the bottom of the casing. Surrounding the tail piece 39 and the boss 40 is a coil spring 90

41 which tends to urge the valve 38 into engagement with the valve seat 33.

The main valve 29 is preferably provided with a depending extension 42 which projects axially through the plug 31 so as to normally engage the top of valve 38 and maintain the same in its open position, to permit the supply to flow from the inlet 11 through the openings 32, 20 and 22 to the outlet 12 in the manner as indicated by the arrows.

The main valve 29 is provided with an outwardly extending stem 43 which projects through an exteriorly and interiorly threaded nipple 44, and a tubular threaded cap 45, which cap is provided with an annular flange 46 arranged to detachably secure an escutcheon 47 in position. The escutcheon 47 is arranged to enclose or conceal the valve casing 10 and the wall opening 14 and engages the outer face of the wall, so that when the parts are set up, the fixture presents a pleasing and attractive appearance. The nipple 44 is preferably formed at its lower end with an annular guide or flange 48 which engages the valve stem 43 and is threaded connected to the sleeve 17 above the flange 48 as at 45°. Preferably positioned between the valve 29 and the annular guide 48 are the washers 49 and the flexible packing 50 for insuring a tight joint between the parts. The valve 29 and the extension 42 are moved into and out of position with respect to the main valve seat 33 by the actuation of a handle 51 that is suitably connected as at 52 to the valve stem 43.

Assuming the parts to be in the position as shown, it will be noted that the main valve and the stop valve are open. That is to say, the supply is free to pass from the inlet to the outlet ports. Should it be desired to cut off the supply for any reason, the handle 51 is actuated so as to bring the valve 29 into engagement with the seat 30, during which movement of the valve 29 the extension 42 forces the stop valve 38 further away from its valve seat 33.

When it is desired to remove the main valve 29 and its associated parts from the casing in order to inspect or renew the same, the handle 51 is first removed from the stem 43 and the cap 46 is withdrawn from engagement with the nipple 44, thus allowing the withdrawal of the escutcheon 47 so as to permit access to the sleeve 17. A suitable tool is then applied to the polygonal head 44 of the nipple 44 so as to partially unscrew the latter from the sleeve 17, which then allows the stem 43 and the extension 42 to be backed out a sufficient distance as to cause the valve 38 to be moved to its seat 33 by the pressure of the spring 41, thus completing cutting off the supply through the casing.

The lower washer 49 in addition to serv-

ing as a support for the packing 50 also acts as a stop to limit the outward movement of the valve 29 and thus prevents the stop valve 38 from being moved to its closed position when the main valve is opened.

If after the main valve 29 and its associated parts are withdrawn from the casing, it is desired to remove the plug 31 and the stop valve casing 35, the same may readily be effected by the insertion of a suitable tool, such as a socket wrench or the like, in the recess 34 of the plug 31, so as to cause the withdrawal of the plug and stop valve from the casing through the extension 13.

It will be seen that by reason of the present construction simple and efficient means are employed for automatically cutting off the supply through the casing immediately upon the removal of the main valve and its associated parts.

Additionally, the various parts may readily be assembled or disassembled for the purpose of inspection or renewal, while the escutcheon conceals all unsightly parts that might detract from the general appearance of the device when installed.

It is understood that the form of the invention shown and described is merely illustrative of a preferred embodiment, and that such changes as fall within the purview of one skilled in the art may be made without departing from the spirit of the invention and the scope of the appended claims.

I claim:

1. In combination, a valve casing having inlet and outlet ports and a lateral tubular extension projecting through a wall opening, a sleeve removably mounted in said extension and having a main valve seat, a coaxial stop valve seat beneath said sleeve, a valve having its stem extending beyond said sleeve for controlling the supply through the main valve seat, a stop valve associated with the stop valve seat for cutting off the supply, said valves being removable from the casing through said extension, means connected to said main valve for normally maintaining the stop valve in its open position, means upon the removal of the main valve from the casing for automatically closing the stop valve, and an escutcheon on said main valve stem for concealing the wall opening and valve casing.

2. In combination, a valve casing having inlet and outlet ports and a lateral tubular interiorly threaded extension projecting through a wall opening, said casing having an interiorly threaded portion between the inlet and outlet ports, a removable sleeve projecting axially into said extension and having an exteriorly threaded lower end engaging said threaded portion and a partition having a central opening, a valve seat formed in said partition, a reciprocating main valve in said sleeve for controlling

- the supply through said opening, an externally threaded plug connected to said threaded portion below said sleeve, said plug having a centrally disposed opening and a stop valve seat, a stop valve connected to said plug and arranged to engage said stop valve seat for cutting off the supply through the casing, means connected to said main valve and engaging said stop valve for normally maintaining the latter in its open position, means adapted to be engaged by a tool for removing the main valve from the casing, means for moving the stop valve into engagement with the seat upon the removal of the main valve, said main valve having its stem extending outwardly beyond said sleeve, and an escutcheon on the main valve stem and concealing the wall opening.
3. In combination, a valve casing having inlet and outlet ports and a lateral tubular interiorly threaded extension projecting through a wall opening, said casing having an interiorly threaded portion between the inlet and outlet ports, a removable sleeve projecting axially into said extension and having an exteriorly threaded lower end engaging said threaded portion and a partition having a central opening, a valve seat formed on said partition, a reciprocating main valve in said sleeve for controlling the supply through said opening, an externally threaded plug connected to said threaded portion below said sleeve, said plug having a centrally disposed opening and a stop valve seat, a stop valve connected to said plug and arranged to engage said stop valve seat for cutting off the supply through the casing, said main valve having an extension adapted to engage said stop valve to normally maintain the latter in its open position, means adapted to be engaged by a tool for bodily removing the main valve from the casing, means for automatically bringing the stop valve into engagement with its seat upon the removal of the main valve.
5. In combination, a valve casing having a sleeve therein, said sleeve formed with a valve seat, a main valve reciprocably mounted within said sleeve and arranged to engage said seat, a stop valve in said casing coaxial with said main valve, a plug removably mounted in said casing and having a stop valve seat therein, said main valve having its stem extending through a wall opening, an escutcheon mounted on said stem for concealing the wall opening, means connected to said main valve and extending through said plug for normally maintaining the stop valve in its open position, and means upon the withdrawal of the main valve from the casing for causing the stop valve to cut off the supply through the casing.
6. In combination, a valve casing having a main valve reciprocably mounted therein and a seat therefor, a stop valve in said casing coaxial with said main valve, a removable hollow plug in said casing, said plug having a valve seat coacting with said stop valve for controlling the supply through the casing, said main valve having its stem extending through a wall opening, an escutcheon mounted on said stem for concealing the wall opening, means connected to said main valve for normally maintaining the stop valve in its open position, and means upon the withdrawal of the main valve from the casing for causing the stop valve to cut off the supply through the casing.
7. In combination, a valve casing having a removable sleeve therein, said sleeve adjacent its lower end being provided with a valve seat and lateral outlet openings, a main valve reciprocably mounted in said sleeve and arranged to engage said seat, a stop valve in said casing coaxial with said main valve, a removable hollow plug positioned between said sleeve and said stop valve and having a seat for said valve, said main valve having its stem extending

through a wall opening, an escutcheon mounted on said stem for concealing the wall opening, means connected to said main valve for normally maintaining the stop valve in its open position, and means upon the withdrawal of the main valve from the casing to cause the stop valve to cut off the supply through the casing.

In testimony whereof I have hereunto set
10 my hand.
